UNITED STATES PATENT OFFICE.

WILLIAM W. BONSON, OF DUBUQUE, IOWA, ASSIGNOR TO BONSON DRY CONCENTRATOR COMPANY, OF DUBUQUE, IOWA, A CORPORATION OF ARIZONA.

DRY-ORE SEPARATOR.

1,073,069.

Specification of Letters Patent.

Patented Sept. 9, 1913.

Application filed March 23, 1911. Serial No. 616,972.

To all whom it may concern:

Be it known that I, WILLIAM W. BONSON, citizen of the United States, residing at Dubuque, in the county of Dubuque and 5 State of Iowa, have invented certain new and useful Improvements in Dry-Ore Separators, of which the following is a specification.

The object of my invention is to largely 10 increase the effective capacity of the dry ore concentrating device set out and described in Letters Patent granted and issued to me on the 3rd day of Jan., 1911, and numbered 980,891. In what it consists and 15 wherein it is differentiated from said patent will be set out in the following specification when taken and read in connection with the drawings accompanying the same and forming a part hereof, in which— 20 Figure 1 is a plan view of the table with the gates and bed thereon and means for reciprocating the table. Fig. 2 is a side view of Fig. 1 showing the end and side 25 pitch of the table. Fig. 3 is an enlarged perspective view of the upper surface of the table with part of the mesh cut away. Fig. 4 is a side view showing its double inclinations.

In the drawings the grid 2 is set upon 30 an air box 4 which is mounted on standards 5 secured to a foundation 6 and adapted to be reciprocated by power applied to a shaft 8 secured to the standards 5 and all adapted to be operated in substantially the same 35 manner as in said before mentioned patent and hence these parts are not herein specifically described.

Referring to the drawings 10 designates 40 the table which has upon it a mesh 12. Upon the mesh 12 are secured ore riffles 15 that are set parallel with each other and in a line with the throw of the table. Over the riffles 15 are secured gangue deflectors 16 which are set at an angle to the riffles 45 15 and at an angle to the throw of the table. Upon the ore riffles and substantially at right angles to the riffles 15 are set one or more gates. In these drawings are shown three gates 18, 20, and 22, which are grooved 50 or cut away at 19 over each riffle 15 and adapted to be adjusted to the top of the riffles or down onto the mesh 12 on the table. The mode of constructing and adjusting the gates may be the same as in the above mentioned patent but I have in these drawings 55

provided a thumb screw 11 having a hook 13 adapted to engage the side of the gate. The deflectors 16 preferably extend diagonally across the table only to the first gate. At the outer side of the table is set another 60 gate 24 which is also adapted to be adjusted down to the mesh 12. Between the gates 22 and 24 is formed an ore concentrating bed having the ends of the riffles 15 contacting with the gate 24 at substantially right 65 angles thereto. Over the riffles 15 on the bed are secured retarders 26 at an angle to the riffles but preferably at a different angle to said riffles than that of the deflectors 16. These retarders 26 commence at the gate 24 70 and extend to within a short distance of the gate 22. At the head 25 which is in reality one side of the table there is secured a hopper 28 adapted to distribute the mass along the head of the table. 75

The table is set on an angle to a horizontal plane in two directions. It inclines from the side of the hopper 28, toward the gate 24 and also inclines endwise from the end 30 to the end 32 as shown in Figs. 2 and 4. 80 As the means whereby these inclinations are accomplished and the manner of adjusting the gates form no part of my invention they are not specifically described herein.

The manner of operating my device is substantially as follows: Power is applied to the shaft 8 which is attached to one side of the table and imparts a reciprocating motion to the table. The air is then turned on through the tube 7 and out into the air 90 box 4 and the mass is delivered onto the side of the table through the hopper where it falls in between the ore riffles and gangue deflectors upon the mesh, then the pressure of air up through the mass, and the motion of the table, immediately stratifies the mass and the ore being heavier than the gangue passes to the bottom in between the riffles 15 and the gangue above the riffles between the gangue deflectors 16. The rapid reciprocating motion of the table throws the ore in a line parallel with the motion of the table and causes it to travel with great rapidity between the riffles 15 on account of the unobstructed passage of the ore in the 105 runways between the riffles and the sharp incline of the table toward the outer end of the riffles. The gangue is held back or turned to one side by the gangue deflectors and off at the end of the table at 32. When 110

the mass comes to the first gate 18 the gangue has largely been disposed of and this gate is adjusted down slightly below the top of the riffles just sufficient to largely skim off the remaining gangue and middlings and, as the table slants toward the end 32, the gangue will pass off in that direction and the ore will pass under the gate and come to the gate 20. As this gate 20 is 5 adjusted down below the gate 18, more of the gangue will be stopped and pass off at the end of the gate 20 while the ore passes under the gate 20 and comes to the gate 22. This gate has been previously adjusted down 10 close to the mesh on the table, and more of the gangue and middlings will be forced off along the side of the gate 22 and at the end of said gate. While the ore passes under the gate 22 the ore and whatever may be left 15 of the gangue and middlings will then pass directly to the gate 24 which has been previously adjusted down onto the mesh on the table and will not allow anything to pass out beneath it. There will then be formed an ore concentrating bed between the riffles 15 and the retarders 26 and when 20 the bed is formed, so that the ore will come to the top of the riffles and the gangue and the middlings between the retarders 26, the gangue and middlings will pass off around 25 the ends of the retarders 26 and be delivered off from the end of the table next to the gate 22. The operator then raises the gate 24 just sufficiently to carry away the pure 30 ore from the bottom of the bed as fast as it is delivered upon the bed from beneath the gate 22.

It will be seen by this mode of construction, with the riffles in a line with the throw 40 of the table and parallel to the incline of the table in one direction and the gangue deflectors at an angle thereto, that as soon as the air and motion of the table have stratified the mass, bringing the gangue to the 45 top, the motion and sharp pitch toward the outer end of the riffles will cause the ore to travel at a great rate of speed down in the runways between the riffles and, since the 50 gangue deflectors are set at an angle to the motion of the table and the table is inclined endwise the gangue will be forced from off the ore to one side, at a great rate of speed. There will however, be as pure a separation 55 as in the former patent above-mentioned, as there is formed substantially the same ore concentrating bed on one side of the table at the end of the ore riffles, but the ore and a small percentage of the gangue and middlings will be delivered onto the bed at a 60 vastly increased rapidity since it is unobstructed in its passage from the hopper to the concentrating bed and is aided in its advancing movement by gravity in the pitch of the table and by the throws of the table.

65 Having now described my invention what

I claim and desire to secure by Letters Patent is:—

1. In a dry ore separator, a table, a mesh on the table, means for forcing a current of air through the mesh, means for imparting motion to the table, riffles upon the mesh set substantially in a line with the throw of the table, and deflectors upon the riffles at an angle to the riffles. 70

2. In a dry ore separator, a table, a mesh on the table, means for forcing a current of air through the mesh, means for imparting motion to the table, riffles secured on the mesh in substantially a line with the throw of the table, deflectors secured on the riffles 80 at an angle thereto, and means for setting the table with the riffles thereon at an angle to a horizontal plane. 75

3. In a dry ore separator, a table, a mesh upon the table, means for forcing a current 85 of air through the mesh, riffles secured on the mesh, deflectors upon the riffles at an angle thereto, means for imparting motion to the table in a line with the riffles and at an angle to the length of the deflectors, and means for setting the table at an incline both 90 longitudinally and laterally. 90

4. In a dry ore separator a table, a mesh on the table, means for forcing a current of air through the mesh, means for imparting 95 a throw to the table, riffles on the mesh set parallel to the throw of the table, deflectors on the riffles at an angle to the riffles, means for dividing the table longitudinally and means for forming an ore concentrating bed 100 on one division of the table at right angles to the ends of the ore riffles. 100

5. In a dry ore separator, a table, a mesh on the table, means for forcing a current of air through the mesh, means for imparting 105 motion to the table, riffles on the mesh set in a line with the throw of the table, deflectors on the riffles at an angle to the riffles, means for dividing the table, and means for forming an ore concentrating bed on one division 110 of the table. 110

6. In a dry ore separator, a table provided with a mesh, means for forcing a current of air through the mesh, means for imparting motion to the table, ore riffles 115 upon the mesh set substantially in the direction of the throw of the table, gangue deflectors upon the riffles and at an angle thereto, a gate dividing the table and at substantially right angles to the ore riffles, means 120 for forming an ore concentrating bed on one division of the table, and means for mounting the table at an angle to a horizontal plane both longitudinally and laterally. 120

7. In a dry ore separator, a table set at an 125 angle to a horizontal plane, a mesh on the table, means for forcing a current of air up through the mesh, means for imparting motion to the table, means for dividing the table into two divisions, ore riffles set on the 130

- mesh on both divisions of the table and in a line parallel with the throw of the table and running at substantially right angles to the means for dividing the table, gangue deflectors set upon one division of the table upon the ore riffles and at an angle thereto, and means in connection with the ore riffles for forming an ore concentrating bed on the other division of the table.
- 5 10. 8. In a dry ore separator, a table set at an incline in two directions, a mesh upon the table, means for imparting a throw to the table, ore riffles secured on the mesh a short distance apart and forming ore runways between the riffles in a line in direction with the throw of the table, gangue deflectors set
- a short distance apart at an angle to the ore riffles and forming gangue runways between said deflectors, a gate dividing the table at the end of the gangue deflectors and at an 20 end of the gangue runways, a gate set at the end of the ore runways and at right angles thereto, and means in connection with said gate and ore riffles for forming an ore concentrating bed on the other division of the 25 table.
- In testimony whereof I affix my signature in presence of two witnesses.
